UNITED STATES PATENT OFFICE

163,626

FAUCET HOSE TEMPERATURE INDICATOR

Marvin E. Palmquist, Cherry Valley, and Edward W. Lundstrom, Rockford, Ill., assignors to Century Tool & Manufacturing Company, Rockford, Ill., a corporation of Illinois

Application August 16, 1949, Serial No. 4,526

Term of patent 14 years

(Cl. D52—7)

To all whom it may concern:

Be it known that we, Marvin E. Palmquist and Edward W. Lundstrom, citizens of the United States, residing at Cherry Valley, in the county of Winnebago and State of Illinois, and at Rockford, in the county of Winnebago and State of Illinois, respectively, have invented a new, original, and ornamental Design for Faucet Hose Temperature Indicator, of which the following is a specification, reference being had to the accompanying drawing, forming part thereof.

In the drawing:

Fig. 1 is a plan view of a faucet hose temperature indicator showing our new design, the indicator being shown on a reduced scale as assembled on a bath spray hose, the latter being indicated in dotted lines;

Fig. 2 is a plan view of the indicator shown substantially full size;

Fig. 3 is a side view of the indicator;

Fig. 4 is a cross-section on the line 4—4 of Fig. 2; and

Figs. 5 and 6 are end views looking at the opposite ends of said indicator.

The dominant features of the design are shown in full lines in the above views.

We claim:

The ornamental design for a faucet hose temperature indicator, substantially as shown and described.

MARVIN E. PALMQUIST.
EDWARD W. LUNDSTROM.
